UNITED STATES PATENT OFFICE.

CHRISTIAN CHRISTIANS, OF BARMEN, GERMANY.

STEAM-GENERATOR.

1,052,887.

Specification of Letters Patent. Patented Feb. 11, 1913.

Application filed October 13, 1911. Serial No. 654,473.

To all whom it may concern:

Be it known that I, CHRISTIAN CHRISTIANS, a citizen of the German Empire, residing at Barmen, in the Province of Rhenish Prussia, Kingdom of Prussia, Germany, have invented certain new and useful Improvements in Steam-Generators, of which the following is a specification.

The invention relates to steam generators, and more particularly to a steam generator in which the circulation of the water is arranged to take place in endless currents, that is to say, in pipes or tubes closed upon themselves and from which the steam is directly drawn, the water being introduced therein in the direction of circulation.

Another feature of the invention consists in providing a feed water heater for the generator, which heater is so situated with respect to the steam generator proper, that the furnace gases flow for the greater part past the latter before reaching the former, and wherein one portion of the heater is so arranged that a free development of steam may take place therein.

In the accompanying drawings which illustrate diagrammatically one form of the steam generator—Figure 1 is a longitudinal section through the generator and setting, taken on the line 1—1, Fig. 3. Fig. 2 is a longitudinal section taken on the line 2—2, Fig. 3; and Fig. 3 is a transverse section taken on the line 3—3, Fig. 1.

Similar characters of reference designate corresponding parts throughout the several views.

Referring to the drawings, *a* designates the evaporating pipes or tubes proper and which run steeply upward and are endless, that is, closed on themselves. At their upper bends they are provided with steam outlets *a'* opening into the steam space of the top drum *b*. Nozzles *c* enter the upper ends of the inner shanks of the pipes *a*; and through these nozzles the feed water is introduced in the direction of the circulation of the water in said pipes *a*. The feed water is received from a feed water heater comprising pipe coils *d* and *f*, and herein after more fully described. In the event of the feed water being dirty, the steep pipes *a* may be provided with outlets for the dirt, their lower bends being then placed in a suitable cylinder or drum, as is well understood.

With the arrangement of endless steep pipes *a*, hereinbefore set forth, the quantity of circulating water is reduced to a minimum, and friction and eddies in the water avoided.

Due to the fact that the steam flows out directly from the circulating current of water and to the direct introduction of preheated water through the nozzles *c*, the percentage of water in the circulating current of water and steam is high. An extremely lively circulation is also set up, and consequently a very high rate of evaporation in the evaporating pipes, because of the fact that the specific gravity of the ascending current at a given place is smaller the nearer said place is to the outlets *a'*. The introduction of preheated water into the descending current also assists the circulation. To heat this feed water, suitable independent sets of pipes *d* and *f* are provided, and are situated in the path of the furnace gases behind the evaporating pipes *a*, the pipes *f*, furthermore, being located behind the pipes *d*. In the example shown, the back pipes *f* of each group are illustrated as located in horizontal position, although they may be arranged vertically. These pipes *f* receive the water, in a direction counter to the flow of furnace gases, from two upper water receptacles or drums *g*, which are fed from a pipe *h*. Pipes *f* open into two lower water receptacles or drums *i* to which are also connected the pipes *d*. These latter pipes are arranged to ascend steeply, so that any steam which may form therein can rise freely and collect in upper drums *k*, thus effecting a powerful circulation in said pipes. The pipes *d* are arranged close to one another to form a guide for the furnace gases; and may, furthermore, be so constructed that serpentine pipes *l* forming a superheater may be accommodated between them. From the upper drums *k* of the feed water heater, water is supplied to the nozzles *c* of the evaporating pipes by means of pipes *m*. Steam collecting in the said drums *k* can

flow through pipes *n* into the top drum *b*. All of the aforesaid steep pipes of the feed water heater may, also be provided with suitable cleaning chambers or dirt outlets, as in the case of the pipes *a*.

5 At normal loads, the pipes *a* alone are able to take up the heat requisite for generating the desired quantity of steam. At overloads, however, the steep pipes *d* of the feed water heater come into action, operating in manner similar to the evaporating pipes *a*. The generator thus readily accommodates itself to various loads.

I claim:—

15 1. In a steam generator: a plurality of endless evaporating tubes provided with suitable steam outlets, and means to admit water to the individual tubes.

20 2. In a steam generator: a plurality of endless evaporating tubes provided with suitable steam outlets, and means to admit water to the individual tubes in the direction of the circulation set up by the heating of said water.

25 3. In a steam generator: a suitable steam drum, a plurality of endless evaporating tubes, one portion of the individual tubes opening into said steam drum, and means to admit water to the individual tubes through that portion of the same located within said drum.

35 4. The combination with a steam generator comprising a plurality of endless evaporating tubes provided with suitable steam outlets, and means to admit water to the individual tubes; of a preheating device for the feed water, adapted to supplement the said generator, and communicating with said means to admit water to the individual tubes.

40 5. The combination with a steam generator comprising a suitable steam drum, a plurality of endless evaporating tubes, one portion of the individual tubes opening into said steam drum, and means to admit water to the individual tubes through that portion of the same located within said drum; of a preheating device for the feed water, adapted to supplement the said generator, and communicating with said means to admit water to the individual tubes and with said steam drum.

45 6. The combination with a steam generator comprising a plurality of endless evaporating tubes provided with suitable steam outlets, and means to admit water to the individual tubes; of a preheating device for the feed water, including a plurality of tubes arranged close to one another to form a guide for the furnace gases, said tubes communicating with said means to admit water to the said individual evaporating tubes.

50 7. The combination with a steam generator comprising a plurality of endless evap-

orating tubes provided with suitable outlets, and means to admit water to the individual tubes; of a preheating device for the feed water, including a plurality of tubes arranged close to one another and forming a chamber for the furnace gases, said tubes communicating with said means to admit water to the said individual evaporating tubes; and a superheating device for the steam produced by said generator, located within the chamber formed by said feed water heater tubes and communicating with the steam outlets.

55 8. A steam generator comprising: a suitable steam drum; a plurality of endless evaporating tubes, one portion of the individual tubes opening into the said steam drum; a water supply drum; a series of pipe coils communicating therewith and in the path of the furnace gases; a collecting drum communicating with said feed water pipe coils; a discharge drum communicating with said feed water pipe coils; means passing into said steam drum and connecting said discharge drum with the individual endless evaporating tubes to supply water thereto; and means connecting said discharge drum with said steam drum to deliver steam of the former to the latter.

60 9. A steam generator comprising: a suitable steam drum; a plurality of endless evaporating tubes, one portion of the individual tubes opening into said steam drum; an upper water supply drum; a set of pipe coils at the rear of the furnace communicating therewith; a collecting drum at the bottom of said furnace communicating with said pipe coils and extending to the front of said furnace; a plurality of ascending pipes communicating therewith at the forward portion of the furnace; a discharge drum at the upper and forward portion of said furnace and communicating with said ascending pipes; means passing into said steam drum and connecting said discharge drum with the individual endless evaporating tubes to supply water thereto; and means connecting said discharge drum with the steam drum to deliver steam of the former to the latter.

65 10. The combination with a steam generator comprising a plurality of endless evaporating tubes provided with suitable steam outlets, and means to admit water to the individual tubes; of a preheating device for the feed water, and including a plurality of independent feed water coils located in the path of the furnace gases and such that the direction of flow of the feed water therethrough is opposed to the direction of flow of the said furnace gases.

70 11. The combination with a steam generator comprising a plurality of endless evaporating tubes provided with suitable steam outlets, and means to admit water to

the individual tubes; of a preheating device for the feed water, and including a plurality of independent feed water coils located in the path of the furnace gases and such that the direction of flow of the feed water therethrough is opposed to the direction of flow of the said furnace gases; and a plurality of tubes communicating with said feed water coils, located at a hotter portion of said

furnace than the said feed water coils and 16 adapted to supplement said steam generator.

In testimony whereof, I have signed my name to this specification in the presence of two subscribing witnesses.
